His Attorney.

UNITED STATES PATENT OFFICE

FREDERICK C. BARTON, OF SCHENECTADY, NEW YORK, ASSIGNOR TO GENERAL ELECTRIC COMPANY, A CORPORATION OF NEW YORK

AMPLIFYING SYSTEM

Application filed November 14, 1925. Serial No. 69,201.

My invention relates to apparatus for amplifying voltage impulses and applying them to a sound reproducing device such as a loud speaker, and has for its principal object the provision of an improved amplifying system that may be operated by alternating current supplied from a house lighting circuit or the like.

It is customary to apply voltage impulses to a sound reproducing device through an amplifying system comprising one or more thermionic amplifiers. This involves the application of different potentials to the load, control and cathode heating circuits of the amplifiers and to the exciting winding of the reproducing device where such a winding is utilized. In order to simplify the control of such systems it is desirable that these potentials be applied through a single source and that the connections to this source be completed only when the voltage applied to the amplifier terminals is maintained within predetermined limits. In accordance with my invention, these results are accomplished by impedance means adapted to be connected to the source in a manner to produce the required potentials and by a voltage regulating device comprising means for controlling the connections of the source to amplifying apparatus.

My invention will be better understood from the following description when considered in connection with the accompanying drawings and its scope will be pointed out in the appended claims.

Referring to the drawings, Fig. 1 shows an amplifying apparatus wherein my invention has been embodied; and Fig. 2 is a perspective view of the device utilized to regulate the plate voltage of the amplifiers.

Fig. 1 shows a transformer 1 comprising a primary winding 2 adapted to be connected to a suitable source through contacts 3 and 4 and leads 5 and 6, a secondary winding 7 for transmitting current to amplifying tubes 8 and 9 and to the field winding 10 of a sound reproducing device 11, a secondary winding 12 for supplying heating current to the cathodes of thermionic rectifiers 13 and 14 through which current is supplied to the

tubes 8 and 9 and the device 11, and a secondary winding 15 for supplying heating current to the cathode 16 of device 9. The voltage impulses to be amplified are applied to the control circuit of tube 8 through leads 17. This control circuit comprises grid 18 and cathode 19 of tube 8 and a negative bias resistor 20 which is connected in parallel with a condenser 21 provided for shunting high frequency currents past the resistor.

A resistor 22 connected to the secondary circuit 7 in series with the resistor 20, resistors 23 and 24, and the field winding 10 is connected between the cathode 19 and anode 25 of tube 8 through the primary circuit 26 of a transformer 27. A condenser 28 connected in shunt to the resistor 22 is provided for shunting high frequency currents past the resistor. Contacts 29 and 30 are provided for connecting a voltage regulating device 70 to the load or anode circuit of the tube 8. It will be observed that the tube 9 is provided with a grid 31 which is connected to the cathode 16 through the secondary circuit 32 of transformer 27 and a negative bias resistor 33 shunted by a condenser 34 and with an anode 35 which is connected to the cathode 16 through windings 10 and 12, rectifiers 13 and 14, winding 7, resistors 20, 23 and 33 and winding 15. Smoothing means shown as condensers 36 and 37 are connected in shunt to the field winding 10.

As indicated by Fig. 2 a glow tube 38 or other suitable voltage regulating means is provided with contacts 29' and 30' for connecting the electrodes 39 and 40 through contacts 29 and 30 to the terminals of resistor 22 and with short circuited contacts 3' and 4' for completing the primary circuit of the transformer 1 through a ballast lamp 45. It will be apparent that this arrangement of contacts has the advantage that it is impossible to energize the amplifying apparatus without at the same time affording it protection against excessive voltage. It will be observed also that the contacts 3' and 30' are made somewhat larger than the contacts 4' and 29' so that incorrect insertion of the glow tube in the receptacle is impossible.

It should be noted that heating current is 100

supplied to the cathode 19 from the main secondary circuit 7 of the transformer 1, the magnitude of this current being dependent on the potential drop produced in resistor 23 by current supplied to the exciting winding 10. This current is substantially constant due to the smoothing effect of condensers 36 and 37 and the exciting winding 10 which acts as a smoothing inductance.

10 The reproducing device 11 also comprises an operating coil 41 that is interposed between the poles 42 and 43 of a core member 44 and is connected to the anode or load circuit of tube 9 through a transformer 46. The 15 sound reproducing device 11 is of the type wherein a diaphragm is operated by means of the operating coil 41 which is located in the strong magnetic field produced by the field coil 10. For convenience of illustration the 20 diaphragm and other details of the device have been omitted.

The operation of the apparatus will be readily understood if it be assumed that the voltage regulating device 38 is placed in the 25 socket comprising contacts 3, 4, 29 and 30. Under these conditions current rectified by the devices 13 and 14 is supplied to the field winding 10 through resistors 23, 22, 24 and 20, the potential drop of resistor 23 is applied to the cathode 19 of tube 8, the potential drop of resistor 22 is applied to the anode or load circuit of tube 8, the combined potential drops of resistors 22 and 24 are applied to the anode circuit of tube 9, and the negative biases of the grids of tubes 8 and 9 are determined by resistors 20 and 33 respectively.

Variation in the current transmitted through the tube 8 is determined by the voltage impulses applied to the grid 18 through leads 17 and these variations in current produced in the anode circuit of tube 8 are utilized to vary the control potential and load current of tube 9 through which the voltage impulses are amplified and applied to the operating coil 41 of the sound reproducing device. It will thus be observed that all the potentials required for operation of the apparatus are applied through a single source and that this source cannot be connected to the apparatus unless it is protected from excessive voltage.

The embodiment of the invention illustrated and described herein has been selected for the purpose of clearly setting forth the principles involved. It will be apparent, however, that the invention is susceptible of being modified to meet the different conditions encountered in its use and I therefore aim to cover by the appended claims all modifications within the true spirit and scope of my invention.

What I claim as new and desire to secure by Letters Patent of the United States is:—

65 1. The combination of a sound producing

device including field and operating circuits, a thermionic amplifier provided with a grid for controlling the transmission of current between a cathode and anode thereof, a second thermionic amplifier interposed between 70 said first named amplifier and said operating circuit for causing voltage impulses applied to said grid to be applied to said operating circuit, current supply means, and means connected to said current supply means 75 in series with said field circuit for diverting heating current through the cathode of the first named amplifier.

2. The combination of a sound producing device including a winding, a thermionic amplifier comprising a grid for controlling the transmission of current between its cathode and anode, means connected between said cathode and anode for transmitting voltage impulses to said winding, voltage regulating 80 means adapted to be connected between said cathode and anode, current supply means, and means operable to prevent the connection of said current supply means to said amplifier before said regulating means is connected 85 thereto.

3. The combination of a sound producing device including a winding, a thermionic amplifier including a grid interposed between a cathode and anode, means connected between 90 said cathode and grid for transmitting voltage impulses to said grid, a source of current, impedance means connected to said source in series with said winding for diverting heating current through said cathode and for 100 diverting current through a circuit comprising said cathode and anode, and means connected between said cathode and anode for supplying impulses to said winding.

4. The combination of a sound producing device including field and operating windings, a thermionic amplifier including a grid interposed between a cathode and anode, means connected between said cathode and grid for transmitting voltage impulses to 105 said grid, a source of current, impedance means connected to said source in series with said field winding for diverting heating current through said cathode and for diverting current through said anode and cathode, and means connected between said cathode and anode for supplying impulses to said operating winding.

5. The combination of a sound reproducing device comprising a winding, a thermionic amplifier comprising a grid for controlling the transmission of current through its output circuit, means for transmitting voltage impulses to said grid, means comprising a transformer, a rectifier and an impedance device connected in said output circuit, voltage regulating means adapted to be connected to said impedance device for regulating the voltage applied to said output circuit through said transformer and rectifier, and means oper- 120 125 130

able to prevent closure of the primary circuit of said transformer until said regulating means is connected to said impedance device.

6. The combination of a sound producing device comprising a winding, a plurality of thermionic amplifiers each provided with a grid for controlling the transmission of current between its cathode and anode, means for transmitting voltage impulses to the grid of one of said amplifiers, means interconnecting the cathode and anode of said amplifier for applying amplified impulses to the grid of another of said amplifiers, means comprising alternating current supply means and a rectifier connected between the cathode and anode of said second mentioned amplifier for applying amplified impulses to said winding, means for transmitting rectified current from said current supply means for heating the cathode of said first mentioned amplifier, and means for transmitting alternating current from said current supply means for heating the cathode of said second mentioned amplifier.

25 In witness whereof I have hereunto set my hand this 13th day of November, 1925.

FREDERICK C. BARTON.
